UNITED STATES PATENT OFFICE.

CHRISTOPHER C. CARTER, OF OMAHA, NEBRASKA.

PHONOGRAPH-RECORD CABINET.

Application filed December 8, 1924. Serial No. 754,554.

The invention relates to phonograph records cabinets, and has for its object to provide a record cabinet which may contain a multiplicity of phonograph records, 5 only one of which can be removed at a time, and provided with means whereby, when one record is removed, the remaining records are prevented from being removed by automatic locking of the delivering mechanism for the 10 various records. Also to provide means whereby when the record, which has been removed, is replaced in the cabinet, the delivering mechanism for the records will be unlocked. 15 A further object is to provide a phonograph record cabinet comprising a plurality of compartments and key operated delivering mechanism cooperating with each compartment, and having indicia thereon, 20 whereby by depressing a predetermined key, a particular record will be forced outwardly from its compartment to a position where it may be easily grasped when removed from the cabinet. 25 A further object is to provide in combination with a phonograph record cabinet a pivoted key, the rear end of said key having pivotally connected thereto an upwardly extending arm terminating in a yoke through 30 which a horizontally disposed record engaging bar extends for forcing a record from the cabinet, said yoke being normally disposed in a recess in the delivery bar and holding the same in retracted position 35 against the action of its spring until the key is depressed. Also to provide above the yoke a plurality of pivoted members between which the yoke is adapted to move for spreading the pivoted members for locking 40 adjacent keys upon the depression of any particular key. 45 A further object is to provide the keys with a vertically disposed rod, which normally extends upwardly into the path of the record, and prevent the record from rolling out of the compartment, and which rod is moved downwardly out of the path of the record upon downward movement of the keys. 50 With the above and other objects in view the invention resides in the combination and arrangement of parts as hereinafter set forth, shown in the drawing, described and claimed, it being understood that changes 55 in the precise embodiment of the invention may be made within the scope of what is

claimed without departing from the spirit of the invention.

In the drawing:—

Figure 1 is a perspective view of the cabinet. 60

Figure 2 is a vertical transverse sectional view through the cabinet, showing the keys in normal position.

Figure 3 is a vertical transverse sectional view through the cabinet showing one of the keys in operative position. 65

Figure 4 is a vertical longitudinal section view through a portion of the casing.

Figure 5 is a side elevation of the record delivering bar. 70

Figure 5^a is a top plan view of the record delivering bar.

Figure 5^b is an end view of the delivery bar. 75

Figure 6 is a side elevation of the yoke carrying bar.

Figure 6^a is a front elevation of the yoke carrying bar.

Figure 7 is a side elevation of one of the pivoted locking members. 80

Figure 7^a is an edge view of one of the locking members.

Figure 8 is a side elevation of the locking bar spring. 85

Figure 8^a is a plan view of the locking bar spring.

Figure 9 is a front elevation of the comb for guiding the key levers.

Figure 10 is a plan view of the record holding rod. 90

Figure 11 is a view in elevation of a plurality of key locking members showing the same in normal positions.

Figure 12 is a view similar to Figure 11, 95 showing the locking members in operative position.

Figure 13 is a perspective view of the key returning spring.

Figure 14 is a top plan view of a portion 100 of the cabinet showing a portion of the operating keys.

Figure 15 is a side elevation of one of the key levers.

Figure 16 is a front elevation of one of 105 the key levers.

Referring to the drawing, the numeral 1 designates the casing of the cabinet, which casing is divided into a plurality of record receiving compartments 2, in which records 110 3 are disposed. The cabinet is provided with a plurality of numbered depressible

keys 4, which control mechanism, whereby any of the records 3 may be forced outwardly from their compartments 2 to a position where they may be grasped and removed from the cabinet. The key mechanism for all of the compartments 2 is the same, and for purposes of illustration and description, the entire mechanism of only one compartment is described and shown. Each key 4

10 comprises a substantially horizontally disposed lever 5, which lever is pivotally mounted at 6 within the lower compartment 7 of the cabinet, and extends rearwardly through the partition 8, and terminates at its rear end in a bifurcation 9, in which bifurcation is disposed the transversely disposed pin 10 of the upwardly extending bar 11. Bar 11 extends upwardly rearwardly of the compartment 2 and is provided with a

15 loop 12, through which the horizontally disposed record engaging bar 13 extends. When the record is in the compartment 2, the loop 12 is in lowered position, and in the recess 14 in the upper side of the record engaging bar 13, as clearly shown in Figure 2. Bar 13 extends through an aperture 15 in the partition 8 and is provided with outwardly extending lugs 16, which overlie the opposite sides of the record 3, therefore the

20 record will be maintained in engagement with the record engaging bar 13 during the record delivering operation. Connected at 17 to the rear end of the horizontal bar 13 is the arm 18 of a spring 19, which spring

25 has its arm 20 anchored at 21 to the rear wall of the cabinet. When the loop 12 is in the bottom of the recess 14, it will be seen that said loop will maintain the bar 13 in retracted position against the action of the

30 spring 19, however when the bar 11 is forced upwardly by the depression of the key 4, which will rock the lever 5, the loop 12 will allow the bar 13 to be forced forwardly by the spring 19, and as the bar 13 is in engagement with the record 3, said record will be forced forwardly to the position shown in Figure 3, where it can be easily grasped by the operator. To prevent the record 3 from being removed from the compartment 2, an

35 upwardly extending rod 22 is provided, which rod is pivotally connected at 23 to the lever 5 forwardly of its pivotal point 6, and which rod extends upwardly through an aperture 23, in the bottom of the record compartment 2 into the path of the record 3, however when the key 4 is depressed, said rod 22 is moved downwardly thereby allowing the record 3 to be removed from the cabinet. To insure the return of the lever 5 to normal horizontal position, as shown in

40 Figure 2, a U-shaped spring 24 is provided, which spring is connected at 25 to the lever 5, and at 26 to the bottom of the cabinet 1. However when a record is replaced in the

45 cabinet the key is depressed, and which ac-

tion will cause the record to engage the forward end of the slidable bar 13 and force the same rearwardly against the action of the spring 19 until the yoke 12 is again received in the recess 14 of the bar 13, at the same time the key will be forced to normal horizontal position, and the upper end of the rod 22 to a position where it will prevent the record from coming out of the cabinet until the key is again depressed.

It will be noted that the key is locked in depressed position until the record which has been removed is replaced in the cabinet, therefore the return of the record to the cabinet is insured. To prevent other records from being removed from the cabinet until the record which has been removed is returned thereto, a plurality of downwardly extending pivoted members 27 are provided, which members terminate at their lower ends in rolls 28 between which rolls the loops 12 are forced when any of the records are delivered from the cabinet. Loops 28, when forced upwardly as clearly shown in Figure 12, between the rolls 28, force said rolls laterally to positions where they will register with adjacent loops 12, and therefore adjacent keys will be locked against operation for delivering records from the cabinet, consequently the operator is compelled to replace the record in its proper compartment before any other records can be removed from the cabinet.

From the above it will be seen that a record cabinet is provided which is simple in construction and provided with means whereby records are delivered therefrom upon depression of a predetermined key, and the cabinet is positively locked against operation until the removed record is replaced in the cabinet.

The invention having been set forth what is claimed as new and useful is:—

1. The combination with a disc record cabinet having a plurality of vertically disposed record receiving compartments, of means for delivering records from said compartments, said means comprising pivoted key levers horizontally disposed, slidable record engaging bars horizontally disposed, spring means for normally forcing said bars forwardly, vertically disposed bars pivoted to the key levers, yokes carried by the upper ends of the vertically disposed bars, said record delivering bars extending through said yokes and provided with recesses in which said yokes are normally disposed, and vertically disposed rods carried by the key levers and extending upwardly forwardly of the records in the path of the records.

2. The combination with a record delivering cabinet having a vertically disposed key control releasing bar, a record delivering bar, a yoke carried by the vertically disposed releasing bar and through which the

record delivering bar extends, of pivoted members above said yoke and adapted to be forced into the path of yokes of adjacent bars for locking adjacent mechanisms.

- 5 3. The combination with a record delivering cabinet having vertically disposed key controlled releasing bars, spring actuated record delivering bars, yokes carried by the vertically disposed key controlled releasing bars and through which the record delivering bars extend, of a plurality of engaged

members pivoted above the ends of the vertically disposed key releasing bars and forming means whereby upon the upward movement of any of the yokes to a position between adjacent pivoted members all of the other bars will be locked against operation by the lateral movement of the pivoted members into the path of said yokes. 15

In testimony whereof I affix my signature.

CHRISTOPHER C. CARTER.
